LEVELING DEVICE

Alfred H. Peters, Davis, Calif.

Application September 9, 1949, Serial No. 114,808

4 Claims. (Cl. 33—73)

1

My invention relates to a leveling device, and it is an object of the same to provide a simple device that can be made at small cost and which will not be liable to get out of order or to wear out except after long-continued use. Neither is it liable to be broken, it being very sturdy.

Another object of the invention is to provide a device of the character described that shall be adapted for use in various situations by simple adjustments and alterations. Thus it can be used as a long-legged device of nearly conventional nature, or it can be changed in very short time—about four minutes—into a compact portable device that can be carried in one hand by a workman in climbing a high building or framework, in passing through narrow and tortuous passages, and the like. In its portable form it can be set up in a window frame or on a sill, on a stump or fence post, an I-beam or a girder and many other places where the ordinary three-legged structure is inconvenient or even impossible of use.

Another object is to provide a construction that is not easily upset or otherwise affected by the wind, which is a serious detriment to the use of conventional devices in many situations.

Referring to the annexed drawings, which are made a part of this application and in which similar reference characters indicate similar parts:

Fig. 1 is an elevation of the device of my invention, with parts broken away.

Fig. 2, a similar view of the upper parts on an enlarged scale, with parts broken away,

Fig. 3, a similar view, illustrating the device with a wind guard, and

Fig. 4, a modification.

In the drawings, reference character 10 indicates a base that has depending lugs 11 near its outer margin, these lugs being spaced away from the edge of the base, and having legs 12, usually three in number, pivotally attached thereto, at 12a.

The base has a central opening which has a wall in the form of a spherical zone that is shown in Fig. 2 at 13 as fitting closely about the under portion of a spherical support 14, or rather about the hemispherical lower portion of the support, which may be shaped as a ball or may have other forms in its upper parts, it being a purpose of my device to permit free swinging in all directions for the said support.

In the form of the invention shown in Fig. 2, a rod 15 is threaded through the ball 14 and

5 into or through a lower portion of a yoke 17 that carries a telescope 18. A level 19 may be mounted on the telescope or otherwise fixed with relation thereto. The rod is held against rotation by means of a locknut 20 bearing against the ball-shaped support 14. At its lower end the rod carries a plumb bob 22 secured thereto by a setscrew 21.

Since much difficulty is encountered in the 10 use of leveling devices in certain parts of the country by reason of wind that upsets them or throws them down from elevated places, I have provided means for minimizing this difficulty or even doing away with it entirely, such means 15 comprising a skirt (Fig. 3) that is built to stand on the ground or any other reasonably level horizontal surface with its lower end and is shaped at its upper end to rest flat against the under surface of the base 10. This will suffice 20 in ordinary circumstances but for greater assurance the base is formed with lugs 11 to which the legs are pivoted and these lugs are so arranged that the skirt 24 fits more or less closely about them and so provides a very secure holding 25 means for the parts. The skirt 24 is shown as imperforate or substantially so, to keep the wind from the plumb bob, but could be made to surround the same only half way or thereabout under some conditions. It will be understood 30 that the staff is adjustable in length by means of the telescoping parts shown or in other manner so that its length can readily be altered when the skirt is applied to the leveling device, as is done mostly under circumstances 35 where a portable device is preferred, though not necessarily so.

It is within the intended scope of my invention to use a roller bearing such as that shown 40 in Fig. 4 in place of the plain rocking bearing of Figs. 1 and 2. In such case the ball bearing will be mounted upon the same base 10 and the aperture at 13' will be the same as in Fig. 2, such shape permitting the staff 15 and connected parts to rock freely. A plain ball race 23 to contain 45 the balls 25 has been found satisfactory, the race being secured to the base by screws or tacks 26 and preventing the balls from escaping, due to the curvature of the ball 14 toward the upper margin of the race 23.

50 It will be convenient in some situations for the user to have means available for raising the levelling device to a higher elevation than the normal low elevation of the portable device as shown in Fig. 3. For such situations I provide 55 telescoping legs on the outside of the skirt, ar-

ranged preferably in the usual tripod formation. Such legs are shown at 27 and it will be seen that they can be extended and secured in extended position by screws 28 when desired.

It will be obvious to those skilled in the art that numerous changes may be made in the devices herein disclosed, all without departing from the spirit of the invention; and therefore I do not limit myself to what is shown in the drawings and described in the specification, but only as indicated in the appended claims.

It should be noted that if the legs be removed all parts may be placed in a cone of metal about 24 to 36 inches high, e. g., the metal skirt, and so can be carried as a compact portable device 15 with a minimum of difficulty.

Having thus fully described my invention, what I claim is:

1. A leveling device comprising a base having an aperture, a support pivotally mounted at said 20 aperture, a plumb bob depending from said support, depending lugs spaced from the aperture about the outer margin of said base, said lugs being adapted for attachment of legs to the base, and a skirt shaped at its upper end to fit against 25 the under face of the base outside said lugs, said skirt extending below the level of said plumb-

bob to protect the same against the action of wind.

2. A device as in claim 1, wherein the lugs are perforated for pivotal attachment of legs thereto, and wherein the skirt fits about said lugs.

3. A device as in claim 1, including legs mounted on said skirt at intervals about the same and projecting below the lower end of the skirt.

4. A device as in claim 3, including means for adjusting said legs in the direction of their length.

ALFRED H. PETERS.
